[57] CLAIM

The ornamental design for a cigarette lighter, as shown and described.

DESCRIPTION

FIG. 1 is a front perspective view of the invention.

FIG. 2 is a rear perspective view of the invention with the invention inverted to show the inside of the invention.

FIG. 3 is a front perspective view of the invention shown attached to a hard pack of cigarettes.

FIG. 4 is a bottom plan view of the invention with the invention attached to a hard pack of cigarettes.

FIG. 5 is a side elevation view of the invention with the invention attached to a hard pack of cigarettes; and, FIG. 6 is a top plan view of the invention.

The broken lines are shown for illustrative purposes only and form no part of the claimed design. The surfaces or portions of the article not shown in the drawing or described in the specifications form no part of the claimed design.
